[57] CLAIM

The ornamental design for a room deodorant dispenser, as shown.

DESCRIPTION

FIG. 1 is a top plan view of a room deodorant dispenser showing our new design;

FIG. 2 is another top plan view thereof showing the dispenser in an open position;

FIG. 3 is a bottom plan view;

FIG. 4 is a side elevation;

FIG. 5 is another side elevation taken 90 degrees from the side shown in FIG. 4;

FIG. 6 is a cross-sectional view along line 6—6 of FIG. 2.
